UNITED STATES PATENT OFFICE.

ADOLPH DAHLSTROM, OF AMERY, WISCONSIN.

BAG-HOLDER.

1,027,464.

Specification of Letters Patent.

Patented May 28, 1912.

Application filed January 11, 1912. Serial No. 670,539.

To all whom it may concern:

Be it known that I, ADOLPH DAHLSTROM, a citizen of the United States, residing at Amery, in the county of Polk and State of Wisconsin, have invented certain new and useful Improvements in Bag-Holders; and I do hereby declare the following to be a full, clear, and exact description of the invention, such as will enable others skilled in the art to which it appertains to make and use the same.

My invention has for its object to provide an improved bag holder, and to this end, the invention consists of the novel devices and combinations of devices hereinafter described and defined in the claims.

The invention is illustrated in the accompanying drawings, wherein like characters indicate like parts throughout the several views.

Referring to the drawings,—Figure 1 is a plan view of the improved bag holder with some parts broken away and with other parts shown in different positions by means of dotted lines; Fig. 2 is a side elevation of the improved bag holder with some parts broken away and with other parts shown in vertical section; and Fig. 3 is a detail view, on an enlarged scale, showing the adjustable lock for the bag supporting arms.

The numeral 1 indicates a portable base or platform provided at one end with a rectangular opening or seat 2 adapted to receive a correspondingly formed shank 3 formed on the lower end of a vertically extended post or standard 4. The lower end of the standard 4 rests on the base 1 and its shank 3 detachably holds the same in a vertical position and against rotation. A brace rod 5 is secured at its intermediate portion to the standard 4 by means of a bolt 6, and its ends diverge forwardly and downwardly and are detachably secured, one to each side of the base 1 by means of screws or otherwise.

Mounted in the standard 4, for vertical adjustment, is a supporting head 7. This supporting head 7 is provided with a pair of rearwardly and horizontally extended spring arms 8 arranged to embrace the standard 4. The free ends of the arms 8 terminate in a pair of laterally spaced and rearwardly extended ears 9. A horizontally extended clamping bolt 10 is passed through the ears 9 and is provided, at its projecting end, with a thumb nut 11 having screw

threaded engagement therewith. As is evident, by tightening the thumb nut 11, the spring arms 8 may be frictionally clamped onto the standard 4 for holding the supporting head 7 in different vertical adjustments. 60

Secured to the supporting head 7, is a horizontally extended bar terminating at its ends in a pair of vertically extended hinge lugs 12. Carried by the supporting head 7, is a pair of coöperating and reversely formed semi-cylindrical bag supporting arms 13 having secured to their outer sides, a multiplicity of outwardly and downwardly projecting bag engaging hooks 14. 65 These hooks 14 are laterally spaced apart and are adapted to be hooked into the upper edge of a bag Y, as best shown in Fig. 2. The bag supporting arms are preferably made of quite heavy spring metal, the purpose of which will presently appear. To the inner ends of the bag supporting arms 13, are rigidly secured a pair of hinge lugs 15 having interlocking and pivotal engagement with the hinge lugs 12. A pair of upwardly projecting eye bolts 16 are secured to the intermediate portions of the bag supporting arms 13 and are adapted to receive and detachably hold a pair of hooks 17 secured, one to each end of a long coiled 70 spring 18. The intermediate portion of this spring 18 extends around the back of the standard 4 which acts as a base of resistance therefor. This spring 18 tends to hold the bag supporting arms 13 in open positions. 75 These hooks 17 are laterally spaced apart and are adapted to be hooked into the upper edge of a bag Y, as best shown in Fig. 2. The bag supporting arms are preferably made of quite heavy spring metal, the purpose of which will presently appear. To the inner ends of the bag supporting arms 13, are rigidly secured a pair of hinge lugs 15 having interlocking and pivotal engagement with the hinge lugs 12. A pair of upwardly projecting eye bolts 16 are secured to the intermediate portions of the bag supporting arms 13 and are adapted to receive and detachably hold a pair of hooks 17 secured, one to each end of a long coiled 80 spring 18. The intermediate portion of this spring 18 extends around the back of the standard 4 which acts as a base of resistance therefor. This spring 18 tends to hold the bag supporting arms 13 in open positions. 85 These hooks 17 are laterally spaced apart and are adapted to be hooked into the upper edge of a bag Y, as best shown in Fig. 2. The bag supporting arms are preferably made of quite heavy spring metal, the purpose of which will presently appear. To the inner ends of the bag supporting arms 13, are rigidly secured a pair of hinge lugs 15 having interlocking and pivotal engagement with the hinge lugs 12. A pair of upwardly projecting eye bolts 16 are secured to the intermediate portions of the bag supporting arms 13 and are adapted to receive and detachably hold a pair of hooks 17 secured, one to each end of a long coiled 90 spring 18. The intermediate portion of this spring 18 extends around the back of the standard 4 which acts as a base of resistance therefor. This spring 18 tends to hold the bag supporting arms 13 in open positions. 95 These hooks 17 are laterally spaced apart and are adapted to be hooked into the upper edge of a bag Y, as best shown in Fig. 2. The bag supporting arms are preferably made of quite heavy spring metal, the purpose of which will presently appear. To the inner ends of the bag supporting arms 13, are rigidly secured a pair of hinge lugs 15 having interlocking and pivotal engagement with the hinge lugs 12. A pair of upwardly projecting eye bolts 16 are secured to the intermediate portions of the bag supporting arms 13 and are adapted to receive and detachably hold a pair of hooks 17 secured, one to each end of a long coiled 100 spring 18. The intermediate portion of this spring 18 extends around the back of the standard 4 which acts as a base of resistance therefor. This spring 18 tends to hold the bag supporting arms 13 in open positions. 105 These hooks 17 are laterally spaced apart and are adapted to be hooked into the upper edge of a bag Y, as best shown in Fig. 2. The bag supporting arms are preferably made of quite heavy spring metal, the purpose of which will presently appear. To the inner ends of the bag supporting arms 13, are rigidly secured a pair of hinge lugs 15 having interlocking and pivotal engagement with the hinge lugs 12. A pair of upwardly projecting eye bolts 16 are secured to the intermediate portions of the bag supporting arms 13 and are adapted to receive and detachably hold a pair of hooks 17 secured, one to each end of a long coiled 110 spring 18. The intermediate portion of this spring 18 extends around the back of the standard 4 which acts as a base of resistance therefor. This spring 18 tends to hold the bag supporting arms 13 in open positions. 115

On the inner face of the supporting head 7, is secured a horizontally extended bar 20, the ends of which are bent to form a pair of oppositely projecting stop lugs 21. These stop lugs 21 are adapted to engage stop shoulders 22 on the inner faces of the bag supporting arms 13 to limit the closing movements of said bag supporting arms. The stop lugs 21 and stop shoulders 22 are so arranged as to limit the closing movements of the bag supporting arms 13 and to hold their free ends laterally spaced apart in predetermined set positions, as shown in Figs. 1 and 3.

Pivottally secured at 23, to one of the bag supporting arms 13, is a lock bar 24, and

mounted in the other of said bag supporting arms 13, is a transversely horizontally extended clamping bolt 25 provided with a thumb nut 26. The lock bar 24 is adapted 5 to span the opening between the free ends of the bag supporting arms 13, when in their closed positions. At its free end, the lock bar 24 is provided with a thumb piece 27, and, in its under edge, is formed a multiplicity (as shown three in number) of laterally spaced notches or open seats 28. These notches 28 are adapted to embrace, one at a time, the clamping bolt 25. It is evident, by tightening the thumb nut 26 on 10 the bolt 25, the lock bar 24 may be clamped onto the adjacent end of the bag supporting arm 13. When the bag supporting arms 13 are in their predetermined closed positions, the notch 28 nearest the thumb piece 27 embraces the clamping nut 25 and holds the bag supporting arms locked together. In case the bag Y is of an unusually small size, the bag supporting arms 13 may be sprung together and either one or the other of said 15 notches 28 brought into engagement with the clamping bolt 25, depending on the size of the bag. In case an unusually large bag Y is to be attached to the bag supporting arms 13, the lock bar 24 may be moved to 20 an inoperative position and the bag supporting arms 13 held in engagement with the bag Y under the tension of the spring 18.

From the foregoing description, it is evident that a bag holder constructed in accordance with my invention may be shipped in 35 a knocked down condition and then put together very quickly by the use of a few tools.

What I claim is:

1. In a bag holder, the combination with 40 a supporting head, of a pair of bag supporting arms, one of which has a hinged connection to said head, an abutment operative on said hinged arm, near its hinged connection, for stopping the same in its normal 45 closing movement, in a predetermined position, said hinged arm capable of being further sprung beyond said predetermined position, and adjustable means for locking said hinged arm in positions closed beyond said 50 predetermined position.

2. In a bag holder, the combination with a supporting head, of a pair of bag supporting arms having a hinged connection to said head, a spring tending to open said arms, 55 means for stopping the normal closing movements of said arms in predetermined

positions, said arms capable of being further sprung together beyond such predetermined positions, and means for locking said arms together, in and beyond said predetermined 60 positions.

3. In a bag holder, the combination with a supporting head, of a pair of bag supporting arms having a hinged connection to said head and also having bag engaging elements, a spring tending to open said arms, means for limiting the opening movements of said arms means for stopping the normal closing movements of said arms in predetermined positions, said arms capable of being further sprung together beyond such predetermined 65 positions, and means for locking said arms together, in and beyond 70 said predetermined positions.

4. In a bag holder, the combination with a standard and a suitable base therefor, of a supporting head mounted on said standard for vertical adjustment, a pair of bag supporting arms having hinged connection to said head and also having bag engaging 80 hooks, a spring tending to open said arms, a stop for limiting the opening movement of said arms, a clamping bolt secured to one of said arms, and a notched lock bar pivotally connected to the other of said arms and having interlocking engagement with said bolt for holding said arms in different closed positions.

5. In a bag holder, the combination with a supporting head, of a pair of bag supporting arms having hinged connection to said head and also having bag engaging elements, a spring tending to open said arms, means for limiting the opening movements of said arms, means for stopping the normal 90 closing movements of said arms in predetermined positions, said arms capable of being further sprung together beyond such predetermined positions, a clamping bolt secured to one of said arms, and a notched lock bar pivotally connected to the other of said arms and having interlocking engagement with said bolt for locking said arms together in and beyond said predetermined 95 positions.

In testimony whereof I affix my signature in presence of two witnesses.

ADOLPH DAHLSTROM.
